(57) **CLAIM**

The ornamental design for a wearable device, as shown and described.

DESCRIPTION

FIG. 1 is a front perspective view of a wearable device showing our new design;

FIG. 2 is a front perspective thereof, showing the band on a closed position;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dash-dot lines in the figures and the areas within the dash-dot lines show portions of the wearable device that form no part of the claimed design.

1 Claim, 8 Drawing Sheets(56)
